ATTORNEY

UNITED STATES PATENT OFFICE

JOHN V. SUNDQUIST, OF NORWOOD, MASSACHUSETTS

CAN TOP

Application filed August 10, 1927. Serial No. 212,038.

The object of this invention is to provide a soldered can top which may be removed without the use of a tool of any character, the cap or top being provided with a handle 5 formed in the special manner indicated below.

A further object is to provide a can with an annular member constituting a permanent portion of the top, at the edge thereof, and detachable cap to be soldered to the annular member, and formed with an extension, normally folded over the cap per se, but adapted to be lifted by the use of the fingers of the individual opening the can, 15 so that it will form a handle of a type permitting of the application of sufficient force to tear the cap from the annular member, along the line where the solder was applied.

With the foregoing and other objects in view, the invention consists in the novel construction and arrangement of elements described, illustrated and claimed, it being understood that modifications may be made within the scope of the claim without de- 25 parting from the spirit of the invention.

In the drawings forming part of this application,

Figure 1 is a view in vertical section showing the upper portion of a can with the 30 particular top disclosed herein.

Figure 2 is a top plan view, the outer series of dotted lines indicating the points at which the solder is applied, and the inner series indicating a down turned flange, permitting of the use of the handle by inserting the fingers therethru, without danger of injuring the latter on a sharp edge of the handle member.

Figure 3 shows the construction of Figure 40 2, in plan, a portion of the cap having been removed by lifting the handle and producing tension thereon.

The wall of a metallic can is designated 10, and an annular member constituting the outer portion of the top and the permanent 45

portion thereof includes an outer downwardly extending flange 11, a channel portion 12, and an upwardly extending flange 13, the top of which will be turned over or provided with sufficient bearing surface to 50 permit of the proper application of the detachable top.

The top or cap per se is designated 15, and is to be soldered to the portion 13 along the dotted line or lines 16 of Figures 2 and 3, 55 and this is the point or line where the tearing or detaching operation is effected.

A handle for the cap 15 is designated 18, and may be of any suitable form, that shown in Figures 2 and 3 being desirable, and this 60 element is provided with an opening 19 surrounded by a flange 20, the latter providing a convenient gripping surface.

The normal position of the handle is that shown in Figure 1 or Figure 2, and when the 65 can is to be opened, the handle is lifted, and sufficient force applied to sever the elements 15 and 13 along the dotted lines 16. The blank of which the top is formed would therefore include a wide portion 18, a wide 70 portion 15, and a narrow neck portion 18'. The tearing operation is commenced at the cutaway portion 22, and then continues laterally in each direction, as tension is applied to the handle. 75

What is claimed is:

A can top comprising an annular member having a centrally arranged opening of considerable size and said member having the outer portion thereof bent angularly and upon itself to form spaced connected gripping flanges to receive the open end of a can and having the flanges secured thereto, said member having the inner portion bent angularly in the same direction with the 80 outer angular portion and having the free edge thereof broadened to form a seat spaced from the annular member, a closure disk resting on said seat and soldered thereto for closing the central opening of the member. 85 90

and the open end of the can and to permit separation of said disk from the member when placed under sufficient strain to open the can, a hand grip connected to one edge of the disk by a reduced neck and normally disposed over the disk by bending the neck, said grip having a centrally arranged opening to permit a person's fingers to be passed through said grip and the latter having the inner edge thereof curved relatively thereto to form a comfortable finger engaging portion.

In testimony whereof I affix my signature.
JOHN V. SUNDQUIST.
